UNITED STATES PATENT OFFICE.

JOHN NEWBERRY REYNOLDS, OF GREENWICH, CONNECTICUT, ASSIGNOR TO
WESTERN ELECTRIC COMPANY, INCORPORATED, OF NEW YORK, N. Y., A
CORPORATION OF NEW YORK.

TELEPHONE SYSTEM.

1,387,180.

Specification of Letters Patent.

Patented Aug. 9, 1921.

Application filed November 21, 1917. Serial No. 203,091.

To all whom it may concern:

Be it known that I, JOHN NEWBERRY REYNOLDS, a citizen of the United States, residing at Greenwich, in the county of Fairfield and State of Connecticut, have invented certain new and useful Improvements in Telephone Systems, of which the following is a full, clear, concise, and exact description.

10 This invention relates to telephone systems, and more particularly to an improved and simplified form of automatic switching apparatus for use in automatic or semi-automatic telephone systems.

15 In step-by-step automatic telephone systems employing two-movement automatic switching apparatus it is customary to employ two slow acting relays and two stepping magnets to control the setting and releasing of the switching apparatus.

20 The main feature of this invention is the provision of automatic switching apparatus in which a single stepping magnet is used for the two directive movements and in 25 which a combined mechanical and electrical controlling device is utilized for controlling the setting and releasing of the switching apparatus.

Another feature relates to the construction 30 of the switch and consists in the simplified manner of translating a vertical movement of the brush shaft into a rotary movement of the brushes.

An additional feature of this invention 35 is the provision of an electromagnetic device having two armatures one of which is electrically rendered slower than the other.

These and other features of the invention 40 will be more readily understood by reference to the detailed description and appended claims.

45 Referring to the drawings: Figure 1 is a side elevation and view of the brush operating mechanism embodying features of this invention, with certain portions of the switch broken away; Fig. 2 is a plan view 50 of the stepping magnet taken upon the line 2-2 of Fig. 1; Fig. 3 is a sectional view of a portion of the switch taken upon the line 55 3-3 of Fig. 1; and Fig. 4 is a perspective view of the operating parts of the switch in conjunction with a diagrammatic showing of a circuit arrangement suitable for operating such switch in a telephone system.

The switch shown in Figs. 1 to 4 inclusive is somewhat similar to that described in my co-pending application, Serial No. 158,190, filed March 29, 1917, except that means are provided for imparting a vertical and rotary movement to the brushes instead of a vertical and transverse movement.

Numerals 5 and 6 designate contact banks representing the line and test terminals of a plurality of lines. These contact banks may be of any suitable and well-known construction and may comprise ten arcuate horizontal rows and ten vertical rectilinear rows of contacts. The contacts are arranged to be wiped over by brushes 50, 51 and 52 shown in Fig. 4 as secured to a cylindrical shell 10. This shell is provided with a spiral slot 25 and is rotatably and slidably mounted on a shaft 11, which shaft is also slidably mounted for vertical movement in the frame 13 of the switch. The shaft 11 at its upper end is provided with a pin 26 arranged to extend through the spiral slot 25, and operates under certain conditions to rotate the cylindrical shell and its brushes. The lower end of the shaft 11 is provided with teeth 70 arranged to be engaged by a vertically operating pawl 12. This pawl is pivoted upon a lever 58 fixed to the armature 98 of a stepping magnet 59. The magnet 59, the details of which will be hereinafter described, and its armature, are supported on an extension 67 of the frame 13. A rod 16, parallel to and adjacent to the shaft 11, is journaled for rotation in the frame 13, and is provided intermediate its ends with a vertical rib 17 which controls the movement of the lever 19. This lever, which is pivoted on a rod 20 (see Fig. 3), is provided with a dog 23 to normally engage notch 24 in the cylindrical shell 10 and a second locking dog 95 22. The dog 22, when lever 19 is actuated, engages a notched bar 21. This bar is secured to the frame and operates with the dog 22 to lock the cylindrical shell in the position to which it has been elevated.

100 When the lever 19 is moved about its axis, the dog 22 thereon will be moved into engagement with a notch on the bar 21 and the dog 23 will be moved out of its slot 24 of the cylindrical shell to permit rotation of the shell. The lower end of the cylindrical shell 10 is provided with a groove 28 into which a forked member 27 extends. This

forked member is rotatably and slidably mounted upon the rod 20 secured to bar 21, and is arranged to move vertically with the lever 19, but rotates independently of this 5 lever.

A sequence controlling device including a side switch is provided to control the circuits and several mechanical movements of the switch. This device comprises a notched 10 disk 69, a ratchet wheel 151, a star wheel 152 and a side switch 82. The notched disk 69 is mounted on the shaft 150 for rotation in the frame (not shown), and is engaged by an arm 15 secured to the lower end of the 15 rod 16 to control the rotation of this rod. The rod 16 is held tensioned by springs or other suitable means (not shown) with the arm 15 normally engaging a notch in disk 69. Secured to the shaft 150 is a ratchet 20 wheel 151 which is arranged to be engaged by the operating pawl 152, pivotally mounted on the armature 66 of the escape magnet 65. A star wheel 152 is secured at the outer end of the shaft 150 and operates an arm 25 153 to control the movement of the said switch indicated at 82.

The stepping magnet 59 is provided with two armatures, 60 and 98, the former quick acting and the latter slow acting. Two iron 30 cores 61 and 62, having magnet spools 190 and 65, are secured to a substantially U-shaped magnetic frame 67. Each of the cores has one end of smaller diameter than the other. The small end of each of the 35 cores 61 and 62 is threaded and extends through apertures in one upright of the frame 67. The cores are secured to said frame by means of internally threaded copper collars 63 and 64, screwed on said cores. 40 Fixed to the frame 67 is an armature support 68. Pivotaly mounted upon the armature support is a lever 69, one end of which operates contact springs 70 and 71 and the other end of which is forked and carries 45 across the forked ends, a flexible strip 72 secured thereto. Fixed to the flexible strip 72 is an armature 60. Since the strip 72, which is the support of the armature 60, is flexible, a better magnetic path is provided, 50 due to the fact that both ends of the armature are permitted to come in contact with the ends of the iron cores 61 and 62, thus reducing the air gap and consequently the magnetic leakage of the cores at this end to 55 a minimum. A bent over portion 99 of the frame 67 has a lever 58 pivotally mounted thereupon. Pivotaly mounted upon one end of the lever 58 is a stepping pawl 12, and secured to said lever in a position adapt- 60 ed to be attracted by the cores 61 and 62, is an armature 98. The armature 98 is normally held away from the ends of the cores 61 and 62 by a spring 73, one end of which is attached to the lever 58 and the other end 65 to an angle arm 74 fixed to the frame. A

wider air gap is provided for the armature 98 than for the armature 60. As a result of these features of design, when current impulses flow through the windings of spools 64 and 65, sufficient magnetism is formed to 70 operate both armatures of the magnet. The armature 98 being heavy and in its operative position, tensioned, retracts at each interruption of current. The armature 60, however, due to the features in design herein 75 described, remains attracted during short interruptions of current.

Referring to Fig. 4, A may represent a calling subscriber's station the line for which is connected with line switch terminals 111, 111 adapted to be engaged by movable contacts 112, 112. Assuming that the subscriber at station A desires connection with a subscriber at a substation B, the operation will be as follows: The subscriber 80 A, upon the removal of his receiver from the switchhook, will automatically have his line connected with the movable contacts 112, 112 in a well known manner, through the operation of a line switch. Following the closure 85 of the line switch contacts, a relay 115, associated with the switch embodying the features of this invention, will be energized over the line circuit through position 1 of side-switch wipers 116 and 117, controlled by 90 this switch. The energization of relay 115 will cause it to open its back contact 121 and close its front contact 122 to ground, thereby completing a parallel circuit, one limb including a slow release relay 123, the 100 other limb including a test relay 124. Upon energization, the test relay 124 becomes locked up over a circuit including its own contact, side-switch wiper 126 in its first and second positions, and a secondary off-normal contact 127 of the selector switch. The slow-releasing relay 123 upon energization opens its back contact 128 and closes its 105 front contacts 129 and 130. At contact 130 a break point in the energizing circuit of the stepping magnet 59 is closed, and when in response to the first impulse from the dial at substation A, the relay 115 retracts its 110 armature, the stepping magnet 59 is energized and attracts its armatures. It will be 115 remembered that the armature 60 of the stepping magnet 59 is slow to release, so that during the series of impulses corresponding to the first digit of the desired number, a 120 circuit is closed from ground, contact 133, side-switch wiper 134 in its first position, winding of escape magnet 65 to grounded battery. The escape magnet 65 attracts its armature 66, thereby drawing down the pawl 152 to engage another tooth of the ratchet 125 wheel 151.

In response to this first impulse, the armature 98 of the stepping magnet 59 is actuated to cause the pawl 12 to elevate the brush shaft one step. During this directive move- 130

ment, the dog 23 engages the notch 24 so that the shell 10 cannot rotate on the shaft 11. As a result of this, the brushes secured to the shell 10 are elevated to the desired 5 group of lines. If it be assumed that the subscriber at substation A first dials the digit 4, four impulses of current will be successively transmitted to the line relay 115, to cause this relay to vibrate its armature. 10 In response to these four impulses of current, the stepping magnet 59 actuates its armature 98 and therefore the pawl 12 to elevate the brush shaft and the brushes 50, 51 and 52 to select the fourth level or group of 15 trunks appearing at the switch.

At the termination of this series of impulses, the energizing circuit of the stepping magnet 59 will be interrupted for a sufficiently long period to permit the slow releasing armature 60 to interrupt the circuit 20 of the escape magnet 65 at contact 133. The escape magnet 65 on deenergizing, retracts its armature 66 and through the agency of pawl 152 rotates the ratchet wheel 151 one 25 step. The disk 69 and the star wheel 152 secured to the shaft 150 are likewise rotated one step. One of the cam surfaces of the star wheel 152 forces the arm 153 to the left, thereby moving the set of side-switch wipers 30 to the second position. Simultaneously the projection on arm 15 passes through a notch to the rear side of disk 151. This operation causes the arm 15 and the rod 16 to which it is secured, to be rotated counter-clockwise. 35 The rib 17 engages the lever 19, thereby removing the dog 23 from the notch 24 and causing the dog 22 to engage the fourth notch in bar 21. As a result of this operation, the cylindrical shell 10 is locked against 40 vertical movement but is made free to rotate.

It will be remembered that the test relay 124 upon the first energization of the line relay 115 was locked up over a circuit completed through the off-normal contact 127, which is not open until the switch has taken 45 its first secondary or rotary step. When the rotary or secondary movement of this selector switch takes place, the secondary off-normal contact is opened. If, however, the first trunk of the selected group is busy, this condition will be indicated by the presence 50 of ground on the test conductor 10, and the locking circuit of the test magnet 124 will be maintained from grounded battery, winding, left-hand armature and spring of the test relay 124, side-switch wiper 126 in its second position, test brushes 52 and the test terminal associated with the first trunk of 55 the fourth group to ground over its test conductor 10.

With the test relay 124 energized in the second position of the side-switch wipers, an energizing circuit is closed for the stepping magnet 59 from grounded battery, 60

winding of this magnet, side-switch wiper 132 in its second position, contact 137, armature 98, conductor 154, contact 136 and armature of relay 124 to ground. The stepping magnet 59 interrupts its operating circuit 70 in the well-known manner and at each attraction of its armature, elevates the brush shaft 11 one step.

Since the cylindrical shell 10 is now locked against elevation, the vertical movement of 75 the brush shaft 11, through the agency of the pin 26 and the slot 25, effects the rotary movement of the cylindrical shell 10 with its sets of brushes, one step for each step that the shaft 11 is elevated with the first energization of the stepping magnet 59 and throughout the period of the secondary operation of the switch, the slow releasing armature 60 is held attracted. During the attraction of the armature 60, the escape 80 magnet 65 is maintained energized.

When an idle trunk in the selected group has been found, the relay 124 is deenergized, causing the deenergization of the stepping 85 magnet 59. Since the stepping magnet 59 now remains deenergized for a relatively long period, the slow releasing armature 60 of this magnet is retracted, thereby interrupting the energizing circuit of the escape magnet 65 at contact 133. The escape magnet 90 then retracts its armature 66 to advance the ratchet wheel 151 together with the disk 69 and the star wheel 152 an additional step. This brings the projection of arm 15 into 95 the notch 158 and also moves the arm 153 outward to bring side-switch wipers 82 into their third or talking condition.

In this position, the line relay 115 is bridged to the talking circuit and is energized throughout the period of conversation. 100 The relay 115 thus maintains its armature attracted to close its contact 122 and thus maintain the slow releasing relay 123 energized. The relay 123 at its front contact 129 closes a circuit from ground through relay 110 143 to grounded battery to energize this relay and close the contacts 142 in the link circuit.

The subscriber at substation A will then 105 send other directive impulses to selectively operate other switches, such as a connector switch, the brushes of which are indicated at 159, to complete the connection to the called subscriber at B.

At the close of the conversation when the 110 subscriber at substation A replaces his receiver on the switchhook, the relay 115 and in turn the slow releasing relay 123 are deenergized. The deenergization of the relay 123 closes an energizing circuit for the escape magnet 65, which extends from 115 grounded battery, armature and contact 128 of relay 123, side-switch wiper 145 in its third position, conductor 157, contact 149, armature and winding of escape magnet 65 120 130

to grounded battery. The escape magnet 65 attracts its armature and thereby interrupts its energizing circuit at the contact 149. The armature 66 in retracting again advances the ratchet wheel 151 one step to bring the side-switch wipers 82 into their fourth position. This operation also brings the projection on the arm 15 to the front side of the disk 69. The arm 15 thus rotates the rod 16 clockwise, thereby causing the hook 90 to withdraw the holding dog 91 from the teeth of the brush shaft 11. The brush shaft 11 drops down under the force of gravity.

15 At this time, however, the cylindrical shell 10 is locked against vertical movement so that the descent of the shaft 11, through the agency of the pin 26 and the spiral slot 25, rotates the cylindrical shell 10 with its 20 brushes, to normal position. At this time the holding dog 23 engages the notch 24 of the shell and withdraws the holding dog 22 from its notch in the bar 21. The shell 10 and the brush shaft 11 then descend to normal 25 position, at which time the off-normal contact 156 is closed. The closure of this contact completes an energizing circuit for the escape magnet 65, which circuit extends to ground through the outer armature and 30 contact 128 of relay 123, side-switch wiper 145 in its fifth position, off-normal contact 156, conductor 161, contact 149, armature and winding of escape magnet 65 to ground and battery.

35 The escape magnet attracts its armature but immediately interrupts its energizing circuit at the contact 149, to bring about the retraction of its armature 66. The armature 66 through its pawl 152 advances the ratchet 40 wheel 156 one step. This causes the arm 153 to engage a second cam surface of the star wheel 152 to permit the moving of the side-switch wipers 82 to normal or position 1. At the same time the projection on arm 45 15 engages the notch 162 of the disk 69. The cycle of operation has now been completed and the switch is in readiness to be operated for another call.

What is claimed is:

50 1. In an automatic switch, passive contacts, active contacts mounted for group and line selecting movements, a cylindrical member to which said active contacts are secured, said cylindrical member being provided with a spiral slot, an actuating member having an element coöperating with said slot, means for operating said actuating member, a controlling device for causing simultaneous operations of said members 55 during group selecting movement of said contacts and for causing one member to move in one direction and for causing the other member to move in another direction during line selecting movements.

65 2. In an automatic switch, passive con-

tacts, active contacts mounted for group and line selecting movements, a cylindrical member to which said active contacts are secured, said cylindrical member being provided with a spiral slot, an actuating member having an element coöperating with said slot, means for operating said actuating member, a controlling device for causing said members to move in the same direction during the group selecting movement of said active contacts and for causing one of the members to move in one direction and for causing the other member to move in another direction during the line selecting movement.

3. In an automatic switch, passive contacts, active contacts mounted for movement in two intersecting planes, a cylindrical member to which said active contacts are secured, said cylindrical member being provided with a spiral slot, an actuating member having an element coöperating with said slot, means for operating said actuating member, a controlling device for causing said members to move in the same direction while the said active contacts are moved in one plane and for causing one member to move in one direction and for causing the other member to move in another direction during the movement of the active contacts in the second plane.

4. In an automatic switch, passive contacts, active contacts mounted for vertical and rotary movement, a cylindrical member to which said active contacts are secured, said cylindrical member being provided with a spiral slot, an actuating member having an element coöperating with said slot, means for operating said actuating member, a controlling device for causing said members to move in the same direction during the vertical movement of said active contacts and for causing said actuating member to be moved vertically and for causing said cylindrical member to rotate during the rotary movement of said active contacts.

5. In an automatic switch, passive contacts, active contacts mounted for group and line selecting movements, a cylindrical member to which said active contacts are secured, said cylindrical member being provided with a spiral slot, an actuating member having an element coöperating with said slot, means for operating said actuating member and a controlling device for locking said cylindrical member to said actuating member during the group selecting movement of said active contacts and for locking said cylindrical member against the movement with said actuating member during the line selecting movement of said active contacts.

6. In an automatic switch, passive contacts, active contacts mounted for movement in two intersecting planes, a cylindrical member to which said active contacts are se-

cured, said cylindrical member being provided with a spiral slot, an actuating member having an element coöperating with said slot, means for operating said actuating member, a controlling device for locking said cylindrical member to said actuating member during the movement of said active contacts in one plane and for locking said cylindrical member against movement with said actuating member during the movement of said active contacts in the second plane.

7. In an automatic switch, passive contacts, active contacts mounted for vertical and rotary movement, a cylindrical member to which said active contacts are secured, said cylindrical member being provided with a spiral slot, an actuating member having an element coöperating with said slot, means for operating said actuating member, a controlling device for locking said cylindrical member to said actuating member during the vertical movement of said contacts and for causing said slot and element to effect the rotation of said cylindrical member during the rotary movement of said active contacts.

8. In an automatic switch, passive contacts, active contacts mounted for vertical and rotary movement, a cylindrical member to which said active contacts are secured, said cylindrical member being provided with a spiral slot, an actuating member having a pin to coöperate with said slot, means for operating said actuating member, a controlling device for locking said members together to effect the vertical movement of said active contacts and for locking said cylindrical member against vertical movement to cause said pin and slot to effect the rotary movement of said active contacts during their second stage of operation.

9. In an automatic switch, passive contacts, active contacts mounted for group and line selecting movements, means for operating said active contacts, a controlling device operative in its normal position to permit group selection, means to move said controlling device in one direction to permit said active contacts to be actuated in a line selecting movement, and means to move said controlling device in the opposite direction to cause release of said active contacts.

10. In an automatic switch, fixed contacts, a member directively operable in one direction only, means for actuating said member, a second member coöperating with the first and arranged for movement in two intersecting planes, movable contacts mounted on said second member and coöperating with said fixed contacts, means for restoring said members, a rotatable controlling device in its normal position permitting said first mentioned element to move said brushes in one direction, means to move said device in one direction to cause said brushes to be moved in a second direction, and to move

said device in the opposite direction to cause the release of said members.

11. In an automatic switch, a bank of contacts arranged in groups, brushes arranged to be moved into engagement with desired contacts in said bank in two selective movements, a shaft, a cylindrical shell supporting said brushes and arranged for rotation upon said shaft, means for locking said shell to said shaft during the first selective movement of said brushes, means for rotating said cylindrical shell on said shaft during the second selective movement of said brushes, a magnet having a pair of armatures one of which is arranged to move said shaft in said selective movements and the other of which is arranged to control the unlocking of said shell from said shaft at the end of the first selective movement.

12. In a telephone system, an automatic step-by-step switch having two selective movements, means including a magnet having a pair of armatures for controlling the selective movements of said switch, means for sending current impulses through said magnet, means for causing one of said armatures to vibrate in synchronism with said impulses, means for maintaining the other of said armatures in operated position during the sending of said impulses, and an auxiliary switch arranged to be positioned under the control of said last named armature.

13. In an automatic switch, fixed terminals, a ratchet member, a brush carriage rotatably mounted upon said ratchet member but normally locked thereto, brushes fixed to said brush carriage and mounted to engage said fixed terminals, a stepping magnet having a slow acting armature and a quick acting armature, means to rotate said carriage on said ratchet member when unlocked from said member, a stepping pawl operated by said quick acting armature and arranged to control the movement of said ratchet member, and means controlled by the slow acting armature of said stepping magnet which causes the unlocking of said brush carriage from said ratchet member.

14. In an automatic switch, fixed terminals, a plurality of brushes having longitudinal and rotary selective movements to engage said fixed terminals, a longitudinally movable rod, a cylindrical shell rotatably mounted upon said rod, said brushes being fixed to said shell, means to translate a vertical movement of said rod into a rotary movement of said shell, means for locking said shell against rotary movements during the first selective movement of said brushes, a combined mechanical and circuit controlling device having a pair of armatures for moving said rod, one of said armatures acting to move said rod in both of said selective movements and the other of said arm-

tures acting to control the operation of said locking means.

15. In an automatic switch, fixed terminals, a plurality of brushes mounted for vertical and rotary selective movements to engage said terminals, a common stepping magnet for both of said selective movements having a circuit controlling armature, an auxiliary switch mechanism, means controlled by said auxiliary switch mechanism for locking said brushes against vertical movement during their rotary movement, said auxiliary switch mechanism being governed by the controlling armature of said 10 stepping magnet.

16. In a telephone system, a plurality of lines divided into groups, an automatic switch having motion in one plane to select groups and motion in a plane at right angles thereto for finding a line in a selected 20 group, a combined mechanical and electrical

controlling device operating said switch in both of said intersecting planes to connect with any of said lines, and an auxiliary switch controlled by said device. 25

17. In an automatic switch, fixed terminals, a shaft, means for moving said shaft upwardly, a cylindrical shell provided with a helical slot, said shell being rotatably mounted upon said shaft and normally 30 locked to said shaft, contact brushes carried by said shell and arranged to engage said fixed terminals, means for unlocking said shell from said shaft, and a pin secured to said shaft and coöperating with said slot 35 when said shell is unlocked to rotate said shell as said shaft is moved upwardly.

In witness whereof, I hereunto subscribe my name this 17th day of November, A. D. 1917.

JOHN NEWBERRY REYNOLDS.
